CLAIM

The ornamental design for a pendant, substantially as shown and described.

DESCRIPTION

FIG. 1 is a perspective view of a pendant showing my new design;

FIG. 2 is a side elevational view of the same, the opposite side view being a mirror image thereof;

FIG. 3 is a top plan view of the same; and

FIG. 4 is an end elevational view of the same, taken from the left end.

FIG.1

FIG.2

FIG.4
